Patented Mar. 21, 1916.

2 SHEETS—SHEET 2.

UNITED STATES PATENT OFFICE.

JOHN SIMA, OF SPRING VALLEY, NEW YORK.

MAIL-BAG CLOSURE.

1,175,999.

Specification of Letters Patent. Patented Mar. 21, 1916.

Application filed November 5, 1914. Serial No. 370,443.

To all whom it may concern:

Be it known that I, JOHN SIMA, a citizen of Besta, Austria-Hungary, residing at Spring Valley, in the county of Rockland 5 and State of New York, have invented certain new and useful Improvements in Mail-Bag Closures; and I do declare the following to be a full, clear, and exact description of the invention, such as will enable others 10 skilled in the art to which it appertains to make and use the same.

This invention relates to improvements in closures for containers and more particularly to means for closing a mail bag and 15 protecting its contents.

The object of the invention is to provide a simple and efficient device for securely locking without a key, a bag or other container for preventing unauthorized persons 20 from obtaining access thereto, it being necessary to know the combination before it can be opened.

Another object is to provide buffing means for the ends of a bag or other container to 25 protect the contents and to insure the container alighting on its protected end when dropped or thrown from place to place.

With the above and other objects in view, the invention consists of certain novel features of construction, combination and arrangement of parts as will be more fully described and claimed.

In the accompanying drawings: Figure 1 represents a front elevation of a mail bag 35 equipped with this improved closure; Fig. 2 is an end elevation of the closure in operative position, the protective cap being removed; Fig. 3 is a similar view with the locking plate in partially open position, 40 whereby the parts are so disposed as to permit the closure proper to be opened; Fig. 4 is a similar view with the closure proper released and ready to be opened; Fig. 5 is a similar view showing the closure in open 45 position; Fig. 6 is an enlarged vertical sectional view taken on the line 6—6 of Fig. 2; Fig. 7 is a similar view taken on the line 7—7 of Fig. 3; Fig. 8 is a similar view taken on the line 8—8 of Fig. 4; Fig. 9 is a perspective view of the closure locking means 50 with the members thereof shown separated and in juxtaposition ready for assembling;

Fig. 10 is a similar view of the closure securing means at the front end thereof; Fig. 11 is a transverse vertical section taken on 55 the line 11—11 of Fig. 1, also on the line 11—11 of Fig. 2.

In the embodiment illustrated, a mail bag B of ordinary material and construction is here shown equipped with this improvement, being here shown provided at its opposite ends with this improved closure or it may have one end only provided therewith, as may be found desirable. This closure comprises an open ring-like frame 1 60 which may be of any desired configuration, being here shown elliptical with lugs 2 and 3 extending inwardly from opposite points which reinforce the frame at these points and are designed for a purpose to be described. The end of the bag B is secured to the inner edge or face of the ring 1 (see Figs. 6 and 11) and a skirt 3' is secured to the outer face thereof and is connected with the bag B at a point spaced from said ring 75 1, forming a chamber C between them.

A cover plate 5 is pivotally mounted on this frame 1 on one of the lugs thereof and the contour of said plate preferably conforms to the contour of the frame 1, al- 80 though not necessarily so. The pivot is here shown in the form of a bolt 6, the head of which is arranged on the inner face of the lug 2 in the chamber C between the bag and the skirt and said bolt extends through 85 said lug and through a longitudinally extending slot 7 formed in one end of the cover 5 and its threaded end engages a threaded recess 8 in the lower face of a locking plate 18 to be described and is em- 90 bedded therein, being thus concealed.

The frame 1 and cover 5 are provided at points diametrically opposite the pivot 6 of said cover, with interlocking elements here shown in the form of a socket composed of 95 a substantially inverted U-shaped member or staple 9 projecting upwardly from the outer or upper face of the frame 1 at the reinforced lug provided end thereof, and outside said member 9 is arranged a guard 100 10 for a purpose to be described.

The cover 5 has a tongue 11 arranged on the edge of its free end, and the free end of said tongue extends flush with said cover.

edge. A recess 12 surrounds said tongue and is designed to receive and house the staple 9 and the guard 10 at the back thereof, the tongue extending into the staple. 5 The guard, when the parts are in interlocked position, is arranged flush with the edge of the cover 5 as shown in Figs. 3, 6 and 7, and completely covers the tongue and socket connection of the frame and cover 10 and renders their location practically invisible to an ordinary observer. When the parts are so disposed, the cover 5 will be secured to the frame 1, the interlocking members 9 and 11 being engaged and disengaged 15 by sliding the cover 5 longitudinally in opposite directions, the slot 7 in said plate, permitting this movement.

The cover 5 has a portion of its outer face cut away from the slotted end thereof 20 for about two-thirds of its length, more or less, being reduced about one-half of the thickness of said cover. A shoulder 14 is formed at the inner end of said reduced portion 13 where it joins the thicker front 25 portion 13' and said shoulder extends obliquely across the cover and is preferably undercut for about one-half of its length for a purpose to be described.

In the outer or upper face of the reduced 30 thinner portion 13 of the cover 5 adjacent the slot 7 thereof, is an angular seat or recess 15 which communicates with a portion of said slot and is designed to receive a cover locking element, here shown in the 35 form of a metal plate 16, corresponding in shape to the shape of the seat 15 and which is of a thickness corresponding to the depth of said seat, so that when said locking plate is disposed in said seat, the outer face 40 thereof will be flush with the outer face of the cover portion 13 and will close the inner portion of the slot 7 and thus prevent the cover from sliding on the bolt 6. This reduced or thinner cover portion 13 also 45 has an arcuate recess 17 arranged transversely thereof and which extends from a point near one side edge of the cover inward to a point beyond the central longitudinal axis of the cover, with its concaved 50 edge arranged toward the slot therein and is designed for a purpose to be described.

A cover releasing plate 18 is pivotally mounted on the bolt 6 and corresponds in shape to the thinner reduced portion 13 of 55 the cover 5, being of a thickness corresponding to the thickness of the shoulder 14 so that when said plate is mounted on the reduced portion 13 of the cover, it completely fills said portion and the outer face 60 thereof is arranged flush with the outer face of the thicker portion 13', of said cover 5. This releasing plate has the recess 8 in its inner or lower face near one end thereof in position to receive the 65 threaded end of the bolt 6 when the parts

are assembled, said bolt forming a pivot on which said plate 18 is adapted to turn. The free edge of this plate 18 is formed obliquely to correspond with the oblique shoulder 14 and a portion of this oblique edge is inclined to fit the undercut portion of the shoulder 14, to assist in holding the plate in closed position. This plate 18 is also provided on its inner face adjacent the nut 8, with a recess or seat 19 corresponding in shape and size to the locking element 16 and is of a depth corresponding to the thickness of said element, the outer end of said seat extending over a portion of the recess 8 and which is designed to receive the locking element 16 when the bag is turned in one position for releasing the cover plate, it being understood that when the locking plate 16 is disposed in the seat 19, of the plate 18, it will be completely 75 housed therein and thus moved out of the recess 15 in the cover plate, thereby uncovering the slot 7 and permitting the cover to be moved longitudinally on the bolt 6.

A lug 20 depends from the lower or inner face of the plate 18 at a point spaced inwardly from the oblique edge thereof and substantially on the longitudinal axis of said plate. The lug 20 is designed to extend into said seat and limit the outward 90 movement of the releasing plate 18, the inward movement thereof being limited by the engagement of its oblique edge with the shoulder 14 of the cover 5.

In the use of this invention, when the 100 parts are in closed locked position as shown in Figs. 2 and 6, and it is desired to obtain access to the bag or other container on which this closure is mounted, the bag must be turned downward into the position 105 shown in Fig. 7, to permit the gravity locking plate 16 to drop out of the recess 15 of the cover 5 into the recess 19 in the releasing plate 18. This plate 18 may then be swung outwardly on the pivot bolt 6 until the lug 110 20 engages the outer end wall of the arcuate seat or recess 17 and when in this position, the gravity lock or plate 16 will have been moved from over the slot 7 in the plate 5, thus permitting the cover to be moved rearward on the bolt 6, thereby disengaging the interlocking tongue and socket members at the free end thereof and permitting said cover to be turned laterally on the pivot 6 and thus afford access to the bag B. The 115 thickened free end of this cover 5 so weights the cover that it will swing by gravity into open position when the bag is turned on one side, it operating in the same manner no matter on which side the bag may be turned.

When the bag is in open position and it is desired to close it, the cover 5 is swung laterally inward until the tongue 11 registers with the socket 9 on the frame 1 and then said cover is slipped forward, causing 130

said tongue to enter said socket and the socket or staple 9 and the guard 10 thereof to enter and be housed in the recess in the end of the cover plate. The plate 18 is then 5 swung inward into closed position with its oblique edge abutting the oblique shoulder 14 of the cover and when in this position, the seat 19 thereof registers with the seat 15 in said cover and the gravity locking element 16 will then drop into the seat 15 and lock the cover against sliding in either direction, whereby the bag will be securely closed and it cannot be again opened until the above described operation is repeated. This 10 closure is preferably housed within a cap 21 having a circumferential flange 22 which conforms in shape to the frame 1 and cover 5 and is adapted to fit snugly thereover and completely inclose said parts. This cap may 15 be secured to the frame 1 by any suitable means, buckles and straps 23 being here shown for this purpose. The outer face of this cap 21 is preferably padded as shown at 24 to form a buffer for protecting the 20 contents of the container. This padded surface is also preferably rounded but this is not necessary, a strap 25 being here shown attached to the outer face of this cap 21 for lifting the bag or for suspending it from a 25 crane or other support.

When constructed as above described, the closure for the bag will be completely housed in the cap and unauthorized persons will thus be unable to obtain access to the bag 30 without first understanding the combination or procedure which is necessary for opening it. Moreover, this padded weighted cap will cause the bag always to alight on the end carried thereby and thus assist in 35 protecting the contents of the bag when roughly handled.

I claim:

1. A closure for containers comprising an oval ring-like frame with inwardly extending members at the opposed ends thereof to form reinforced widened portions at these points, a guard extending at right angles from said frame at the edge of one end thereof, an inverted U-shaped member 45 spaced laterally from the inner face of said guard and arranged in alinement therewith, a pivot extending through the other reinforced end of said frame on the same side having the guard, a cover plate having 50 a slot at one end engaged with said pivot and a tongue at its other end with its terminal spaced inwardly from said end a distance equal to the thickness of said guard, said tongue having recesses on 55 its opposite sides whereby it is interlocking engaged with the inverted U-shaped member on the frame when the cover is in closed position, the guard extending flush with the peripheral edge of said cover and 60 completely concealing the connection be- 65
2. In a closure for containers, the combination of an open ring-like frame with inwardly extending members at opposed points to form reinforced widened portions at these points, a pivot extending through one end of said frame; a cover plate having a slot at one end engaged with said pivot, 70 coöoperating means at the other end of said plate and frame for interlocking engagement, said cover having a portion of its outer face cut away and terminating in an obliquely disposed shoulder undercut for 75 about one-half of its length, the cut-away portion of said cover having an angular seat in its outer face with the slot in the cover extending inwardly into said seat and outwardly beyond it, a locking plate fitting in 80 said seat and of a thickness equal to the depth thereof, said cut-away cover portion having an arcuate recess extending from a point near one side edge thereof to a point beyond the central longitudinal axis of said cover, 85 the concave edge of said recess being disposed toward the slot, a cover releasing plate shaped to conform to the cut-away portion of the cover and to fit flush in said portion when applied, said releasing plate 90 being mounted to swing on said pivot and having a recess on its inner face positioned to register with the angular recess on said cover plate when the parts are in closed position, said recesses corresponding in 95 shape, the free edge of said releasing plate being inclined to fit the under-cut portion of the shoulder on said cover plate, the recess in said releasing plate being of a depth sufficient to receive and completely house 100 the locking plate, and a lug extending laterally from the inner face of the releasing plate and positioned to engage the arcuate recess in the cover plate for limiting the 105 outward movement of the releasing plate, the pivot which connects the frame and plates having its head arranged on the inner face of said frame and its other end embedded in and housed in the releasing plate to prevent unauthorized removal of 110 said pivot.
3. The combination of an open ring-like frame, a container having one end arranged within said frame and secured to the inner face thereof, a skirt secured to and depending from the outer face of said frame and connected at its lower end with said container to form a chamber between them, a pivot extending through one end of said frame with its head housed and concealed 115 in said chamber, a cover plate for said frame, mounted to swing on said pivot, co-operating means on said frame and cover for interlocking engagement, means for locking said engaging means in engaged po- 120
4. The combination of an open ring-like frame, a container having one end arranged within said frame and secured to the inner face thereof, a skirt secured to and depending from the outer face of said frame and connected at its lower end with said container to form a chamber between them, a pivot extending through one end of said frame with its head housed and concealed 125 in said chamber, a cover plate for said frame, mounted to swing on said pivot, co-operating means on said frame and cover for interlocking engagement, means for locking said engaging means in engaged po- 130

sition, and a cover releasing plate mounted to swing on said pivot with the end of the pivot embedded in the inner face of said releasing plate whereby the location of said pivot is completely concealed and its head protected against unauthorized access.

In testimony whereof I have hereunto set

my hand in presence of two subscribing witnesses.

JOHN SIMA.
